The ornamental design for a hoof dressing tool, as shown and described.

DESCRIPTION

FIG. 1 is a right, rear perspective view from the above of the hoof dressing tool showing my new design;

FIG. 2 is a right front perspective view from below of the hoof dressing tool of FIG. 1;

FIG. 3 is a right side elevational view of the hoof dressing tool of FIGS. 1 and 2;

FIG. 4 is a left side elevational view of the hoof dressing tool of FIGS. 1-3;

FIG. 5 is a top plan view of the hoof dressing tool of FIGS. 1-4;

FIG. 6 is a bottom plan view of the hoof dressing tool of FIGS. 1-5;

FIG. 7 is a rear elevational view of the hoof dressing tool of FIGS. 1-6; and,

FIG. 8 is a front elevational view of the hoof dressing tool of FIGS. 1-7.

The portions of FIGS. 1-8 shown in broken lines form no part of the claimed design.
